UNITED STATES PATENT OFFICE.

HENRY L. DOHERTY, OF NEW YORK, N. Y.

METHOD OF REGULATING COMBUSTION OF GASEOUS FUEL.

1,150,842.

Specification of Letters Patent.

Patented Aug. 17, 1915.

Application filed May 15, 1911, Serial No. 627,133. Renewed February 18, 1915. Serial No. 9,183.

To all whom it may concern:

Be it known that I, HENRY L. DOHERTY, a citizen of the United States, and a resident of New York city, in the county of New York and State of New York, have invented certain new and useful Improvements in Methods of Regulating Combustion of Gaseous Fuel, of which the following is a specification.

10 This invention relates to a method of regulating combustion of gaseous fuel, and in particular to an improved method of carrying out the combustion of such a fuel to produce a long, voluminous, slow burning flame.

15 The object of my invention is to secure a more uniform generation of heat throughout the furnace, retort-oven, or whatever apparatus is being heated by the combustion, whereby the retorts or material which is the subject of the heating are subjected to a very uniform and even temperature.

20 In the present methods of conducting combustion in a retort furnace, for example, the producer gas is burned with undiluted air, with the production of a short hot flame in contact with a few of the retorts, highly heating the same, while the remaining retorts are without the direct action of the flame and heated only by the hot products of combustion. As the combustion gases flow through the oven they give up more and more of their heat to the retorts, gradually falling in temperature, meanwhile.

25 As a result, the retorts which are last heated by the gases are in contact with relatively cool gases compared with those in the immediate region of combustion. The result of this is that if the time given to burning

30 off a charge is regulated by the time required for the completion of the operation in the hottest retorts, the material in the relatively cooler retorts will not be thoroughly carbonized, while if the duration of the operation is regulated by the time required to carbonize the charge in the cooler retorts, it will be unduly and unnecessarily prolonged so far as concerns the charges in the hotter retorts.

35 By my method, I am able to secure a prolonged and diffused combustion, so that the generation of heat is distributed throughout

the oven chamber, with the result that all of the retorts are subjected to substantially the same temperature.

55

My invention consists, briefly stated, in an improvement over present used methods of burning producer or other gases in furnaces, retort ovens or the like in which I add combustion or other inert gases to the air supplied to support the combustion and of apparatus for carrying out such process. The effect of this is to greatly reduce the velocity of reaction at the place of mixture of the producer gas and air. The oxygen of the air being diluted with a relatively large volume of inert gases a considerably longer time elapses before all of the combustible constituents of the producer gas have come into reactive proximity to oxygen. As a consequence of this, combustion of the gas takes place throughout a much larger region of the retort oven. In fact, the proportion of flue gas may be so adjusted that combustion will not be completed until just before the gases discharge from the oven. The result of this is that I am able to bathe each and every one of the retorts in the oven chamber with a flame of burning gas of just the right temperature to secure the best results in carbonization. The heating of the charges in the several retorts is thus made very uniform. Besides this advantage, I secure another important result—i. e., increased life of the retorts and setting due to the possibility of working with a uniform and moderate temperature. Each retort is exposed to only the degree of heat that is requisite for perfect carbonization. It is not necessary to overheat some retorts in order to properly heat the remainder.

40 In the drawings, I have shown an apparatus capable of carrying out my improved process.

Figure 1 is a longitudinal section through one of the air recuperators and part of the retort oven of a gas bench on the line A—B of Fig. 2. Fig. 2 is a half cross-section of the gas bench on the line C—D of Fig. 1 and a half elevation. Fig. 3 is a part longitudinal section through the gas producer of the bench on the line E—F of Fig. 2.

45 The usual method of operating the apparatus shown is as follows:—A deep bed of

fuel is maintained in the gas producer 1, the fuel being supported by the grate 2. The combustion of the fuel is supported by the air admitted through the dampers 3. Drip plates 4 are placed in the front of the producer, to which water is supplied through the pipe 5. The water runs onto the uppermost drip plate and thence the excess passes from plate to plate, the drip from the lower plate falling into the water pan 4' beneath the grate. The heat of the fuel bed evaporates the water in the pan 4' and on the drip plates 4, the vapor produced cooling the ironwork of the grate and ash pit and then 10 passing into the fuel bed and cooling the same. In the ash zone of the producer just above the grate 2, the cooling effect of the vapor is due chiefly to the absorption of sensible heat, by the vapor, from the ash. In 15 the upper part of the fuel bed the cooling effect is due to the heat taken up from the incandescent fuel and rendered latent through the reaction between the water vapor and the incandescent carbon, viz.: 20

The oxygen of the air admitted also reacts with the fuel to produce carbon monoxid according to the well known reaction 30 $C + O = CO$. The producer gas thus generated ascends from the fuel bed and passes through the nostrils 6 into the oven chamber 7, where it is burned by the oxygen of the secondary current entering through the air nostrils 8. The products of the secondary combustion sweep around the retorts, as indicated by the arrows, and escape from oven-chamber 7 through the ports 9 of the uppermost recuperator flues 10 of the recuperators 11 and 12. From the flues 10, the combustion gases pass through the recuperator flues 13 to the stack flues 23. In 40 passing through the flues 13 a large part of the sensible heat which the combustion gases carry out of the retort oven 7 is transferred to the secondary draft current passing upward through the flues 14 of each recuperator. As the combustion gas flues 13 of each recuperator are located in the vertical flues 14 of the corresponding recuperator, the secondary draft current is caused to sweep around the flues 13 and take up the heat of the combustion gases passing therethrough. The heated draft current passes thence to the air nostrils 8 as before described. 50

In my present process which is the subject of this application, I modify the process described above by introducing a predetermined volume of flue gas into the secondary draft current. This is accomplished by means of the injectors 15. As shown, these are actuated by air under pressure taken from the main 16. The air discharging through the nozzle 17, assisted by the natural draft of

the bench exerted upon the recuperator, as well as upon the producer 1, induces a flow of air and combustion gases into and through the injectors 15 and into the recuperator flues 14. The air enters the injectors through the dampered air inlets 18, while the combustion gases enter through the passages 19. The flow of the combustion gasses through 19 is controlled by the dampers 20. By manipulating the dampers to 75 18 and the dampers 20 it is obvious that for any setting of the air valves 21 the relative proportion of induced air and combustion gases may be varied at will.

The commingled air and products of combustion ascend through the vertical flues 14, sweeping around the horizontal flues 13, which carry the combustion gases, and pass through the group of passages 22. From 80 passages 22 the mixture of air and combustion gases passes through the nostrils 8 into the retort oven as already described.

The effect of the presence of the combustion gases in the secondary draft current is to dilute the air so that the velocity of the 90 combustion taking place between the gas from the nostrils 6 and the air of the secondary draft entering through nostrils 8 is reduced. Instead of burning with a short flame, the producer gas burns with a long 95 diluted flame of reduced intensity, that sweeps through the chamber 7 enveloping the retorts therein. If desired, the proportion of products of combustion in the secondary draft current may be made sufficiently 100 great to so prolong the combustion of the gas that the flame will extend up to and, indeed, into the off-take flues 10.

By this improvement I am able to produce a long flame of burning producer gas which 105 bathes the retorts with a flame of substantially uniform temperature. It is thus possible and practicable to secure a substantially uniform temperature in all of the retorts. As a result, the charges in all of the retorts 110 may be carbonized to a uniform extent and in the same interval of time. This insures the production of gas and coke of uniform quality and thus diminishes the amount of care and supervision that must be expended 115 upon the subsequent purification of the gas.

Having described my invention, what I claim is:

The method of securing a uniform heating effect in a furnace chamber which comprises 120 introducing into said furnace chamber a current of combustible gas, forming a mixture of air and products of combustion, heating said mixture by the sensible heat of the products of combustion discharging from 125 said furnace chamber, conducting the so-heated mixture of air and products of combustion into said furnace chamber to burn said combustible gas, the proportion of products of combustion in said mixture 130

being such as will cause the said combustible gas to burn with a prolonged, diluted flame that will substantially fill said furnace chamber, whereby the contents of said chamber is subjected throughout to the direct action of the heating flame.

Signed at New York city in the county of

New York and State of New York this 13th day of May A. D. 1911.

HENRY L. DOHERTY.
